UNITED STATES PATENT OFFICE.

JAMES W. CRYDER, OF PHILADELPHIA, AND WILLIAM CLAIR HIDLAY, OF BLOOMSBURG, PENNSYLVANIA.

COIN-WRAPPER.

1,405,296.

Specification of Letters Patent. Patented Jan. 31, 1922.

Application filed December 23, 1920. Serial No. 432,780.

To all whom it may concern:

Be it known that we, JAMES W. CRYDER and WILLIAM C. HIDLAY, citizens of the United States, residing, respectively, at 5 Philadelphia and Bloomsburg, in the counties of Philadelphia and Columbia, State of Pennsylvania, have invented a new and useful Coin-Wrapper, of which the following is a specification.

10. This invention has reference to wrappers especially designed for wrapping coins, checks or the like, it being the object of the invention to provide a wrapper having novel means to permit the wrapper to be opened to 15 release the contents thereof.

A further object of the invention is to provide means of this character to eliminate the necessity of throwing a package to the floor or on the corner of a desk to break the 20 wrapper to release the contents.

With the foregoing and other objects in view which will appear as the description proceeds, the invention resides in the combination and arrangement of parts and in 25 the details of construction herein described and claimed, it being understood that changes in the precise embodiment of the invention herein disclosed, may be made within the scope of what is claimed, without departing from the spirit of the invention.

Referring to the drawing:—

Figure 1 illustrates a front elevational view of a wrapper constructed in accordance with the present invention;

Figure 2 illustrates an end elevational view of the same; and

Figure 3 illustrates a plan view of the inner surface of a blank, of which the wrapper is formed.

Referring to the drawing in detail, the reference character 5 designates the body of a wrapper which is formed preferably of heavy paper, the size of the wrapper being 45 controlled by the size of the coin or checks to be wrapped or housed thereby, it being understood however that the wrappers are to be formed in standard sizes to contain predetermined numbers of coins or checks.

A line of perforations indicated at 6 is 50 formed in the body portion 5 in spaced relation to one edge of the blank, the ends of the line of perforations being also spaced from the ends of the body portion 5, so that the wrapper will not be weakened at points 55 along the ends thereof.

Positioned on the inner surface of the wrapper and extending along the line of perforations is a cord 7 which is glued or otherwise secured to the wrapper, the ends 60 of the cord extending through the openings at the ends of the line of perforations as at 8, to provide extensions to be grasped by the fingers of the operator to tear the wrapper along the line of perforations to open the 65 same.

The ends of the body 5 are glued together so that the wrapper, when in use, will be of 70 tubular formation, and of a diameter to embrace the coin positioned therein.

In the use of the device, as before stated, if it is desired to break the package to release the contents thereof, it is only necessary to pull the cord 7, with the result that 75 the wrapper is torn along the line of perforations, the contents thereof falling into the user's hand.

Having thus described the invention, what is claimed as new is:—

A wrapper including a tubular body portion, said body portion having a line of perforations formed therein, and disposed longitudinally of the wrapper, the ends of the line of perforations terminating at points in spaced relation from the ends of the 85 wrapper, a cord positioned behind the line of perforations and having its ends extending through openings in the wrapper, said string adapted to tear the wrapper along the line of perforations.

In testimony that we claim the foregoing as our own, we have hereto affixed our signatures in the presence of a witness.

JAMES W. CRYDER.
WILLIAM CLAIR HIDLAY.

Witness as to James W. Cryder:
JOSEPHINE M. GINSBORN.
